INVENTOR.

Oliver J. Moersch

BY

Thomas Damrell

ATTORNEY.

UNITED STATES PATENT OFFICE.

OLIVER J. MOERSCH, OF DETROIT, MICHIGAN.

NECKTIE.

Application filed March 3, 1927. Serial No. 172,272.

My invention relates to a new and useful improvement in a neck tie, and while I have illustrated the invention as applied to a four in hand neck tie, from the description of the invention it will become readily apparent that it may be used with other types of neck ties.

It is an object of the present invention to provide a neck tie which may be tied and which, after being tied, may be placed upon and removed from the collar or neck without in any manner disturbing or untying the bow or knot into which the tie had been formed.

Another object of the invention is the provision in a tie of this class of a slidable retaining member, permitting the sliding of the tie to increase the dimensions of that portion which extends around the neck so that the releasing member may be easily accessible for releasing the tie from its embracing position on the neck.

Another object is the provision in a tie of this class of a grooved reinforcing member in which a non-elastic securing member is adapted to slide.

Other objects will appear hereinafter.

The invention consists in the combination and arrangement of parts hereinafter described and claimed.

The invention will be best understood by a reference to the accompanying drawings which form a part of this specification and in which,

Fig. 1 is a perspective view of a four in hand tie embodying the invention.

Fig. 2 is a fragmentary inside elevational view of the neck-surrounding portion of the tie.

Fig. 3 is a fragmentary view similar to Fig. 2 with parts removed and parts shown in section.

Fig. 4 is a sectional view taken on line 4-4 of Fig. 2.

Fig. 5 is a sectional view taken on line 5-5 of Fig. 2.

Fig. 6 is a sectional view taken on line 6-6 of Fig. 2.

As shown clearly in Fig. 1 the four in hand tie comprises a pair of fabric portions 9 and 10 which may be made from any suitable material adapted for use as a tie and tied into a four in hand knot 11. These tie forming portions are usually formed of overlapped material, and extending on the inner surface of the portion 10 at one side is a non-elastic cord 12 which is secured by the stitches 13 to

the fabric. This cord 12 is also secured by the stitches 14 to the fabric, so that one side thereof is in fixed relation to the tie body 10. The cord projects outwardly from the upper end of the tie body 10 and extends around a groove or channel 15 formed in the reinforcing block 16 which is secured by suitable stitching between the overlapped portions 17 and 18 of the adjustable fastening ribbon 19, this ribbon being preferably made of non-elastic material. This ribbon is provided, intermediate its ends, with an adjustment buckle 20 of a form well known, and at its end, with a hook 21 adapted to engage the eyelet 22 which is secured to the upper end of the tie forming portion 9, a suitable reinforcing strip 23 being secured around the attached end of the buckle 22 to reinforce the end of the tie portion 9. The cord, after extending around the block 16 projects into the channel 24, a reinforcing block 25 being mounted at the upper end of the tie forming portion 10, this reinforcing block 25 being of less width than the tie forming portion at this end, so as to provide the channel 24 and the channel 26 in which the secured end of the cord 12 engages. The other end of the cord, after passing through the channel 24, projects downwardly of the tie forming portion 10, and is free for movement. The free end is provided with a button 27 which serves as a gripping member, and the fastened end is provided with a button 28, preventing slipping of the member 12 in the stitches.

When the one using the tie is about to insert it in a collar, the hook 21 is fastened to the eyelet 22, thus securing the tie forming portions 9 and 10 together to form an uninterrupted strip similar to the customary four in hand tie. The tie, when inserted in the collar, is then used in the manner of the ordinary tie, the four in hand knot 11 being formed. If desired, however, the tie may be extended around an object of the size desired, and the knot 11 formed. When the knot is formed while the tie is on the collar, the usual operation is gone through and the ends of the tie forming portions 9 and 10 project sufficiently above the four in hand knot 11 to extend into the collar so as to conceal the attachment of the ribbon 19 with the portion 10 and the eyelet 22 with the ribbon 9. When it is desired to remove the tie from the collar, the portion 10 is pulled downwardly, this pull being exerted primarily on the fastened end of the cord 12 and causing the free end

of the cord to travel around the block 16 and permitting the end of the ribbon 19 to withdraw from the end of the tie forming portion 10, as shown in Fig. 2, thus enlarging the portion of the tie which extends around the collar and permitting a shifting of the tie relatively to the collar so as to bring the hook 21 into a position accessible to the user, so that the hook 21 may be disengaged from the eyelet 22. Thus the tie is removable from the collar without disturbing the four in hand knot 11.

When placing the tie in the collar the ribbon 19 is extended around the collar, and the eyelet 22 is engaged by the hook 21. This engagement is had only after the ribbon 19 is withdrawn from the tie forming portion 10 as shown in Fig. 2. After the engagement of the hook and eyelet, the strain is exerted on the free end of the cord 12 causing this cord to move around the block 16 and bring the end of the tie forming portion 10 into engagement with the end of the ribbon 19, as shown in full lines in Fig. 3, the movement being from the position shown in dotted lines in Fig. 3.

In this manner the tie is brought to the desired degree of tautness about the collar, and all of the appearances of an ordinary tie is presented.

It has been found by experience that when the tie is in use by having the free end of the cord 12 positioned at the lower edge of the tie forming portion 10 so that it is adjacent the lower edge of the collar, more efficient and satisfactory results are obtained as an undue slipping of the tie when in this position is reduced to a minimum.

By providing the reinforcing block 25 on the tie forming portion 10, a buckling of the end of the portion 10 is prevented so that a free and easy movement of the cord is accomplished, when desired. The use of the channel bearing block 16 also permits an easy riding of the cord around the block 16, so that the adjustment may be very easily and quickly made. The use of the reinforcing strip 23 also prevents a squeezing of the end of the tie forming portion 9 into small dimensions, and keeps it distended throughout the full width of the eyelet 22.

With a tie of this kind there is provided a detachable hand-tied tie which is easily operated, of simple and durable structure, and one of very neat appearance.

While I have illustrated and described the preferred form of my invention, I do not wish to limit myself to the precise details of structure shown, but desire to avail myself of such variations and modifications as come within the scope of the appended claims.

Having thus described my invention what

I claim as new and desire to secure by Letters Patent is:

1. A neck tie of the class described adapted for passage around a collar and being formed into a knot subsequent to the passage around said collar, comprising: a pair of members formed from the fabric constituting the tie and adapted for being tied about each other intermediate their ends, to provide said knot, the upper ends of said members extending partially around said collar; an attachment member connected to the upper ends of each of said members and encircling said collar, said attachment member being detachably connected to the upper end of one of said members, the other end of said attachment member being permanently connected to the upper end of the other of said members, and movable bodily relatively thereto within certain limits; and a non-elastic slideable member on said other member for drawing said attachment member into close relation to the upper end of said other member. 85

2. A neck tie of the class described comprising: a pair of tie forming members of the fabric constituting the tie; an attachment member for connecting the upper ends of said tie forming members; hook and eye members for detachably connecting said attachment member to the upper end of one of said tie forming members; a cord secured at one end to one of said tie forming members and extending in slideable relation through said attachment member and thence downwardly along the side of the other of said tie forming members to provide a draw string for drawing the end of said attachment member into close engagement with the upper end of said other tie forming member. 90

3. A neck tie of the class described, comprising: a pair of tie forming members of the fabric constituting the tie; an attachment member for connecting the upper ends of said tie forming members; hook and eye members for detachably connecting one end of said attachment member to the upper end of one of said tie forming members; a rigid groove bearing block mounted in the other end of said attachment member; and a cord secured at one end adjacent one edge of the other of said tie forming members and extending around and in engagement with the groove of said block, the other end of said cord being free and extended along the opposite edge of said other tie forming member to provide a draw string for drawing the end of said attachment member into close engagement with the end of said other tie forming member. 105 110 115

In testimony whereof I have signed the foregoing specification.

OLIVER J. MOERSCH.
